UNITED STATES PATENT OFFICE.

FRANK B. JOHNSTON, OF ROSELLE PARK, NEW JERSEY, ASSIGNOR TO AMERICAN
SAFETY DEVICE COMPANY, A CORPORATION OF NEW YORK.

SCAFFOLDING DEVICE.

1,127,445.

Specification of Letters Patent.

Patented Feb. 9, 1915.

Application filed August 12, 1913. Serial No. 784,331.

To all whom it may concern:

Be it known that I, FRANK B. JOHNSTON, a citizen of the United States, residing in Roselle Park, in the county of Union and State of New Jersey, have invented certain new and useful Improvements in Scaffolding Devices, of which the following is a specification.

This invention relates to improvements in scaffolding devices, and the object of the invention is to provide means whereby the use of scaffolding devices such as are used in the erection of high buildings, may be made more secure than hitherto, and for this purpose my invention consists of an improved locking device applied to scaffolding devices, whereby the members or sections composing the platforms are locked together in a secure manner so as to cause the entire platform to be interlocked so that in the event of any single cable breaking, or any part of the scaffolding machine getting out of order, that machine, and that portion of the platform would be supported by the remaining portions of the platform as all these portions of the platform are securely locked together.

In the accompanying drawings, Figure 1 shows a side view of a platform having the hoisting drums thereon, and supported from an outrigger fixed to a portion of the building, the platform having my improved safety device theron, Fig. 2 is a side view of a scaffolding device with my improved safety device shown thereon, Fig. 3 is a plan view of a portion of the platform showing my improved safety device, and Fig. 4 is a side view, partly in vertical section, of a portion of the platform showing my improved safety device.

Similar reference numerals indicate corresponding parts throughout the figures of the drawings.

Referring to the drawings, the building column is indicated by 10, and a cross-beam arranged horizontally is indicated at 11. To the cross-beam 11 an outrigger 12 is secured by means of a stirrup 13, which has a cross-piece 14, held in position by nuts 15. The outrigger is embraced by straps 20 through the lower end of which a bolt 21 passes, which bolt also passes through an eye at the upper end of the cable 25. The cable 25 is wound on a drum 26 at one side of which a gear-wheel 27 engaged by a pawl

28 is arranged, and the drum is supported by the shaft 29 in the frame 30 of the scaffolding machine. A loose pulley 31 serves to guide the cable 25. An operating lever 32 pivoted on the drum-shaft and carrying a pawl 33 engaging a ratchet-wheel 37 on the drum, serves for manual operation of the latter. The scaffolding device as described is well known and forms no part of this invention. It is customary at the present time to have the frame 30 of the scaffolding device constructed in U-shape. Cross-beams are supported at their ends, each in two of said U-shaped frames, and the planking is supported on the cross-beams, with one end of the planks overlapping the next, as is, for instance, shown in Fig. 2, where one end of the plank 35 overlaps the adjacent end of the next plank 36.

According to the present invention, for supporting the plank-members a cross-beam or putlog 39 is arranged, supported on the frame 30 by bolts 71, and a locking means is provided, whereby the ends of the members 35 and 36 of the platform are securely locked together, so as to prevent the possibility of slipping. For this purpose, above the planking 35, 36, is a cross-beam consisting of two parallel angle-irons 40 and 41, which are joined together by bolts 42, which pass through a block 43, the latter of a size in excess of the width of the frame 30, as shown in Fig. 3. The angle-irons 40 and 41 extend the width of the frame, and can extend across the width of the platform, as shown in Fig. 1. These angle-irons 40 and 41, with their block 43, are vertically movable on the frame 30 of the machine, and rest upon the members forming the platform. Above the angle-iron frame 40 and 41, a cam-shaped locking device 50 is arranged, which has its handle-portion 51 shaped so as to give an easy grip, and which is pivoted at 52 to the frame 30 and has a nose or cam portion 53 adapted to rest against the block 43. By downward pressure on the handle 51, the locking device 50 has its nose or cam 53 pressed against the block 43. The cam thereby forces the angle-iron frame 40, 41, downwardly against the ends of the platform-members indicated by 35 and 36. The clamping of these members together between the lower cross-beam 39 and the upper cross-beam 40, 41, serves to bind the platform-members throughout the

length of the platform. By this arrangement these locked members of the platform act as a suspension device and in the event of any cable of any particular machine 5 breaking or any machine being out of order, so as to induce its rapid descent, the suspension thus formed, brought about by the locked ends of the planks, serves to support the entire platform in position and prevents 10 danger to the operatives.

In Fig. 1, the improved locking device is clearly shown as applied to the platform adjacent to which the scaffolding devices or drums are arranged. In this figure is also 15 shown another, lower, platform on which the operatives may work. In this case, the upper platform serves as a roof to the workmen operating on the second or lower platform, and this roof acts to prevent the workmen 20 being injured by falling stone and the like. The lower platform is suspended by rods 61, which have an enlarged upper portion 62, supported by a stirrup 63, which stirrup 63 is engaged by a bolt 64 passing 25 through the lower cross-beam or putlog 39. The members of the lower platform, indicated by 65 and 66, are locked in position by a cam device 67 like the device 50, and by 30 this interlocking of the members of the platform at their overlapping ends, a very secure platform is obtained.

I have shown one embodiment of the invention, but it is clear that changes may be made therein without departing from the 35 spirit of the invention, as defined in the appended claims.

I claim:

1. In a scaffolding device, a platform having sections with their ends overlapping 40 each other, cross-beams under the overlapping ends of the bottom members, cross-beams above the overlapping ends of the top members, cables supporting the said bottom cross-beams, independent and independently 45 operated hoisting mechanisms for raising and lowering said cables, and means for forcing the bottom and top cross-beams toward each other, and for maintaining them tightly clamped together.

50 2. In a scaffolding device, a platform having sections with their ends overlapping each other, cross-beams under the overlapping ends of the bottom members, cross-beams above the overlapping ends of the

top members, cables supporting the said bottom cross-beams, independent and independently operated hoisting mechanisms for raising and lowering said cables, and a cam for forcing said cross-beams toward each other, and for maintaining them tightly 60 clamped together, said cam being operated by means within the sides of the platform.

3. In a scaffolding device, a platform having sections with adjacent ends, independent and independently movable cross-beams 65 under the adjacent ends of said adjacent sections, cross-beams above the adjacent ends of the adjacent sections, cables supporting the bottom cross-beams, and means for forcing the top and bottom cross-beams toward each other for maintaining them 70 tightly clamped together.

4. In a scaffolding device, a platform having sections with adjacent ends, cross-beams under the adjacent ends of said adjacent sections, cross-beams above the adjacent ends of said adjacent members, frames supporting the bottom cross-beams, cables supporting said frames, said cross-beams above said sections being connected with and movable upon said frames, independent and independently operated hoisting mechanisms for raising and lowering said cables, and means connected with said frames for forcing said top and bottom cross-beams toward each other, and for maintaining them 80 tightly clamped together.

5. In a scaffolding device, a plurality of spaced lower cross-beams, planks laid across said cross-beams to form sections of a continuous platform, spaced upper cross-beams above said lower cross-beams, independent and independently movable cables supporting said lower cross-beams, said upper and lower cross-beams projecting over the adjacent ends of the adjacent sections of said platform, and means external to said planks for forcing said upper and lower cross-beams together, and for maintaining them 90 tightly clamped together.

In testimony, that I claim the foregoing as my invention, I have signed my name in presence of two subscribing witnesses.

FRANK B. JOHNSTON.
